UNITED STATES PATENT OFFICE.

LEROY A. WESTON, OF ADAMS, MASSACHUSETTS.

BAIL FOR RETAINING COTTON IN CANS.

Application filed July 16, 1923. Serial No. 651,983.

To all whom it may concern:

Be it known that I, LEROY A. WESTON, a citizen of the United States of America, residing at Adams, county of Berkshire, 5 Commonwealth of Massachusetts, have invented certain new and useful Improvements in Bails for Retaining Cotton in Cans, of which the following is a specification.

This invention relates to improvements 10 in cotton receiving cans. More particularly it has reference to the attachment of a bail at or near the upper edge of a can which is used to receive the rope-like stream of cotton slivers as it comes from the machine. 15 Heretofore, it has been very objectionable and wasteful on account of the stream of rope-like cotton after the can becomes full it runs over the top onto the floor, resulting in a large waste of the product when the cans 20 are rolled along the floor from one part of the room to another.

I have discovered that by attaching one or more bails at the upper end of the can, that the rope-like product of cotton can 25 effectively be retained therein by first gently pressing the same downward into the can against the spring mounted platform and then swinging the bail or bails upward and over the upper end of the can.

30 The very light rope-like cotton can then be prevented from escaping from the can, or as stated above, it can be retained in the can permitting it to be rolled about the floor from one point to another in the room. 35 Heretofore these cans have not been provided with any means of preventing the very light rope-like cotton product from escaping from the can.

Reference is made to the accompanying 40 drawings which form a part of the specification for a full description of the invention and in which—

Fig. 1 is a plan view of one of the cans showing the bails in their elevated positions.

45 Fig. 2 is a vertical sectional view on the line 2—2 of either Fig. 1 or Fig. 3 showing the interior construction, and with the rope-like strands of cotton retained under the bails, and

50 Fig. 3 is a partial side elevational view showing the bails in their operative position for retaining the cotton in place.

Referring to the drawings in detail by reference numerals,

55 1 designates the can as a whole of the usual diameter and height, the usual diam-

eter is from six to 12 inches and the usual height is substantially thirty-six inches so that the cans are comparatively high in proportion to their diameter. The cans therefore when filled contain a long column of very light material which up to the present time it has been extremely difficult to retain in the cans and to prevent its escaping from the top. Moreover, this very light material cannot be subjected to very much pressure, for when the very light rope-like product is drawn out of the can the product will be materially injured.

By means of my improvement little, if any pressure, is applied to the product, and at the same time it is effectually retained in the can.

2 designates a spring supported platform which is located at substantially one third of the distance from the bottom of the can. 75 3 is a coiled spring located under the platform and resting on the bottom 4. Attached near the upper end of the can are the bails 5 and 6 which are arranged at right angles 80 to each other, as shown. These bails are pivotally attached to the receptacle by means of the ears 7 and 8 which are located below the lower edge of the bead 9 which is preferably formed with a curved outer edge 10, with which the bails may frictionally engage, if desired, to retain them in their elevated position. The rope-like product of cotton as it comes from the machine has somewhat the appearance indicated 90 at 11. The bails 5 and 6 are lowered into the positions at the side of the can, as indicated in dotted lines, when the product is being fed into the can. After a suitable quantity has been received in the can, the spring mounted platform 2 is understood to assume a somewhat lower position than that shown in full lines in Fig. 2 and may assume the dotted line position in Fig. 2 when the product is withdrawn to form a thread 95 or other article.

100 After the can is filled it is gently pressed downward by the operator into the can to permit the bails 5 and 6 to be turned upward into the full line positions shown in the figure. The product then assumes the positions under the bails, and, by reason of its springy condition will automatically be retained in the can, by reason of the combined action of the inherent springy condition of the material itself and the upward pressure of the spring mounted platform 105 110

2. The rope-like material is therefore effectually retained in the can permitting it to be readily rolled on the floor about the room without any danger of the material 5 escaping from the can onto the floor.

It will therefore be seen that I have provided a very simple and effectual means for retaining the very light rope-like cotton in place and one that is comparatively inexpensive and very useful for the purpose intended.

It should be stated that the bails are retained in their elevated position by the upward action of the material which is elastic 15 to a certain extent.

What I claim is:

1. A can for the purpose described having a bail pivotally attached at or near its upper end for receiving on its under side 20 the upward pressure of a cotton product when in a rope-like condition, and bead means around the upper edge of the can for temporarily retaining the bail in an upright position.

25 2. In combination, a can-like receptacle for receiving a rope-like cotton product, means for preventing the same from es-

caping from the receptacle when the same is filled above its upper edge, said means comprising a plurality of bails pivotally attached near the upper end of the can and arranged substantially at right angles to each other and designed to assume positions above the can when filled with the said cotton product to receive the upward elastic pressure of the product to prevent its escape from the receptacle as described, and means for temporarily retaining the bails in their upright positions.

3. A receptacle for the purpose described, 40 having in combination, a spring mounted platform therein, bails pivotally attached to the receptacle; the upper end of the receptacle having a beaded part and with which the bails engage to frictionally retain the same in their upright positions, said bails being for the purpose to prevent the elastic contents from escaping from the receptacle, the same being retained therein by the combined action of the elastic quality of the material itself and the spring mounted platform, as described.

LEROY A. WESTON.
